[57] ABSTRACT

An elongated inflated balloon has its intermediate portion passing through and secured in an opening in the wall of a hollow body so that an inner end portion of the balloon is disposed inside the body and its outer end portion extends outwardly, while gas communication between the inner and outer portions is maintained through the intermediate portion of the inflated balloon. While the outer end portion is held by hand of a user, the balloon is introverted by finger pressure directed longitudinally inwardly against its outer end, thus increasing gas pressure inside the balloon and providing reaction force for its propulsion along with the body when the balloon is released.

SELF-PROPELLED AERIAL TOYS

This invention relates to new and useful improvements in amusement devices or toys, and in particular the invention concerns itself with an aerial toy or flying toy which is self-propelled by energy of an inflated balloon.

While it is old in the art to provide toys which are propelled by energy of an inflated balloon, the balloon used in such toys is of the jet type in which the inflating gas is discharged and the balloon must be re-inflated for each occasion of use. By contrast, it is the principal object of this invention to provide a flying toy in which the propelling balloon is sealed and inflated at all times, the energy of propulsion being derived by manual introversion of the balloon to increase the gas pressure therein and thus provide a reaction force for propulsion purposes. When this force is expended in the course of a single flight, the introverted balloon resumes its initial shape and is in readiness for the next flight without requiring any inflation at all.

The device of the invention is simple in construction, highly entertaining in operation, easy to use even by young children, and lends itself to economical manufacture.

With the foregoing more important object and features in view and such other objects and features which may become apparent as this specification proceeds, the invention will be understood from the following description taken in conjunction with the accompanying drawings, wherein like characters of reference designate like parts and wherein:

FIG. 1 is a side elevational view of the aerial toy of the invention;

FIG. 2 is a fragmentary view, partly in elevation and partly in section, taken substantially in the plane of the line 2—2 in FIG. 1;

FIG. 3 is a perspective view of the toy body per se; and

FIG. 4 is a fragmentary side elevational view showing the manner in which the device is held and manipulated during use.

Referring now to the accompanying drawings in detail, the self-propelled aerial toy or flying toy of the invention is designated generally by the reference numeral 10 and consists of two principal components, namely, a hollow body 12 and an elongated balloon 14.

The body 12 preferably is in the form of a hollow ball or sphere, which may be shaped to simulate a baseball or a football, or the like, and the body 12 has its wall provided with an opening 15 to receive the balloon 14 as hereinafter described. It is also provided with a plurality of vent apertures 16 communicating with the atmosphere.

The balloon 14, as already stated, has an elongated form and is provided at one end thereof with an inflating neck 17 which may be tied or otherwise closed off as at 18 when the balloon is inflated by blowing air into it through the neck.

The inflated balloon 14 is connected to the toy body 12 by passing the balloon through the aforementioned opening 15 so that the inner end portion 14a of the balloon is disposed inside the hollow body 12, while the outer end portion 14b of the balloon extends outwardly from the body, as will be apparent from FIGS. 1 and 2. Preferably, means are provided for positively retaining the body 12 and the balloon 14 in assembled relation. Such means comprise a plurality of substantially triangular detents 19 which are formed integrally with the wall of the hollow body 12 at the edges of the opening 15 and project inwardly into the body in mutually convergent relation, the adjacent edges of the detents 19 being spaced apart to provide V-shaped notches 20, as is best shown in FIG. 3.

When the inflated balloon 14 is passed through the opening 15 into the hollow body 12, the intermediate portion of the balloon becomes grippingly seated in the V-shaped notches 20 by the restrictive action of the detents 19 on that portion of

the balloon. Nevertheless, the opening 15 is sufficiently large for the intermediate portion of the balloon to remain unobstructed and maintain air communication between the inner portion 14a and the outer portion 14b of the balloon.

5 Conveniently, the aforementioned detents 19, formed integrally with the wall of the body 12, may be bent inwardly during formation of the opening 15, as will be clearly apparent.

When the body 12 and the balloon 14 are assembled as described, the toy is used by holding the outer end portion 14b of the balloon with one hand as indicated at 21 in FIG. 4. The index finger 22 of the other hand is then pushed against the outer end 14c of the balloon so that by longitudinally inward pressure in the direction of the arrow 23, the balloon becomes introverted or invaginated as indicated at 14'. This introversion of the balloon may continue until the index finger 22 has passed through the opening 15 in the body 12, thus in effect bringing the outer end 14c of the balloon inside the inner end portion 14a within the body 12, as illustrated in FIG. 4. The introversion of the balloon causes the gas pressure therein to be increased and the inner end portion 14a thereof to become expanded as shown by the dotted lines in FIG. 4, such expansion being possible by provision of the vent apertures 16 in the body 12, communicating with the atmosphere.

20 25 The device may then be pointed in a desired direction of flight and by simultaneously releasing both hands from the balloon and imparting a directional push thereto, the energy derived from the increased gas pressure inside the balloon will provide a reaction force for propulsion of the device in the desired direction of flight. When the flight is ended, the balloon will resume its initial form as in FIG. 1, in which it is still inflated and ready for the next flight. The action of the device may be further enhanced if, at the introverting stage shown in FIG. 4, the index finger 22 is given a partial turn or

30 35 rotation, as a half-turn for example, which causes the introverted portion of the balloon to become axially twisted. Then, when the balloon is released, the axial twist will impart a rotative force to the body 12, thus causing both the body and the balloon to rotate while in flight.

40 45 Although in the foregoing there has been described and shown the preferred embodiment of the invention, various modifications and equivalents may be resorted to within the spirit and scope of the invention as claimed.

What is claimed as new is:

45 1. A self-propelled aerial toy, comprising in combination a substantially spherical hollow body provided with an opening communicating with the interior thereof, and an elongated inflated balloon having an intermediate portion thereof secured in said opening so that in inflated outer end portion of the balloon is disposed exteriorly of said body and an inflated inner end portion thereof is disposed in the interior of the body, said opening being of such size that gas communication is maintained between the inflated outer and inner end portions of the balloon through said intermediate portion thereof which is secured in the opening.

50 55 2. The device as defined in claim 1 wherein said hollow body is also provided with vent apertures communicating with the atmosphere.

3. The device as defined in claim 1 wherein said opening in said body is provided with substantially V-shaped notches having the intermediate portion of said balloon grippingly seated therein, whereby to constitute means for securing the balloon in said opening.

60 65 4. The device as defined in claim 3 together with detents formed integrally with said body and projecting inwardly thereinto in mutually convergent relation, said detents being spaced from each other and defining said notches therebetween.
